UNITED STATES PATENT OFFICE.

LEO G. STRANSKY, OF PUKWANA, SOUTH DAKOTA.

VACUUM-FEED TANK FOR AUTOMOBILES.

Application filed September 22, 1922. Serial No. 589,779.

To all whom it may concern:

Be it known that I, LEO G. STRANSKY, a citizen of the United States, residing at Pukwana, in the county of Brule and State 5 of South Dakota, have invented certain new and useful Improvements in Vacuum-Feed Tanks for Automobiles, of which the following is a specification.

This invention has reference to attachments for vacuum feed tanks for automobiles and its object is to provide for the regulation of the air feed to the intake side of the engine so as to prevent the breaking of the vacuum in the vacuum tank where 10 little suction is necessary to draw the gasoline from the supply tank to the vacuum tank.

The invention comprises a T-shaped casting with a central stem ending in a male 20 thread and a cross pipe ending at the ends in valve structures with the central pipe and the terminal valves sloping downwardly and each valve including a ball member in a casing having a range of movement to 25 and from the terminal part of the valves and capable of rising against a valve seat slotted to permit the incomplete closure of the seat and to drop onto an opening which may be closed by the ball valve.

30 The hole in the middle or male threaded projection has a passage much larger than the two in the valve sleeves combined so that the main suction is in the center male threaded projection. Since the greater 35 amount of suction is through this center male threaded projection this will cause proper working of the vacuum feed at all speeds of the engine.

By plugging the female connection in this 40 casting and attaching an elbow to the middle male connection, the same vaporizer may be used on the Ford and Chevrolet types of engines and other cars, trucks and tractors, while the vaporizer may be attached to the 45 vacuum feed tank of such cars as the Dodge, Studebaker and Buick.

The invention will be best understood from a consideration of the following detailed description taken in connection with 50 the accompanying drawings, forming part of this specification, with the understanding that the invention is not confined to any strict conformity with the showing of the drawings, but may be changed and modified 55 so long as such changes mark no material departure from the salient features of the

invention as expressed in the appended claims.

In the drawings:—

Figure 1 is a perspective view of the invention as applied to vacuum feed tanks of the Buick or other makes of automobiles. 60

Fig. 2 is a front elevation of the vaporizer attachment.

Fig. 3 is a central vertical section there- 65

through.

Fig. 4 is a view similar to Fig. 2 but modi- 70

fied for automobiles of the Ford and Chev- 75

rolet type of automobiles.

Fig. 5 is a section on the line 5—5 of 70

Fig. 4.

Referring to the drawings, particularly to Fig. 1, there is shown a vacuum tank 1 such as is employed, for instance, on the Buick automobile and may be taken as typical of 75 other vacuum tanks.

In connection with the vacuum tank, there is provided a vaporizer 2 shown separately in Figs. 2 and 3, and on a larger scale than and separate from the vacuum tank. 80

The vaporizer comprises a casting 3 in the form of a pipe having depending necks 4 and 5 at the ends and at an intermediate point another neck 6 also depending and of somewhat greater length than the necks 4 85 and 5. There is a duct 7 extending throughout the length of the pipe 3 and joining other ducts 8, 9 and 10 in the necks 4, 5 and 6.

Each neck 8 and 9 terminates at the lower 90 end in a valve seat 11 provided with notches or recesses 12, 13, respectively, at the lower ends.

Applied to the necks 4 and 5 are closures or valve containers 14 and 15, respectively, screwed onto the necks 4 and 5. The container 14 is provided at the lower end with a perforation 16 and the container 15 is provided at the lower end with another perforation 17, which may be of larger size than the perforation 16. The closures or containers 100 14, 15 are each provided with milled bands 18 permitting the manipulation of these containers by the fingers of the human hand if so desired, or they may be operated by means of a suitable tool. 105

The neck 6 is somewhat longer than the necks 4 and 5 and terminates at the lower end in a male screw continuation 19 which is attached to a male connection on top and near center of vacuum tank 1. The neck 25 has a 110 female connection, to which an elbow is applied and to which is screwed one end of pipe

- 21, usually of flexible metal type to be ultimately joined by coupling 22 to a connection 23 designed to enter the engine mainfold 24, in Fig. 1.
- 5 The upper end of the neck 6 is provided with an internally threaded extension 26 to receive a screw plug 26 when the attachment is used with the Ford or Chevrolet automobiles.
- 10 Lodged in each container 14 and 15 is a ball valve 27 adapted to the seat 11 and capable of moving into and out of the seat, being prevented from being lost by the respective container 14 or 15.
- 15 In attaching the vaporizer to vacuum feed tanks, but little suction is necessary to draw the gasoline from the rear or supply tank to the vacuum tank, wherefore the ball valves cause sufficient resistance to allow the engine 20 to draw sufficient air out of the vacuum tank and draw the gasoline from the rear tank.
- 20 In operation, the suction is mainly through the neck 6 and this suction is modified by the presence of the necks 4 and 5 as 25 further modified by the presence of the valves 27 and the by-passes about the valves to the valve seats with the air intakes through the passages 16 and 17.
- 25 The several passages are so proportioned 30 as to cause proper working of the vacuum feed at all speeds of the engine.
- 30 By plugging the female connection 25 and attaching the elbow 20 to the middle male connection, the same vaporizer may be used 35 on the Ford, Chevrolet, and many other cars, trucks and tractors, by drilling and threading a hole in intake manifold.
- 35 The vaporizer is especially adapted to the removal of carbon from within the engine.
- 40 To do this place a cup under the sleeve with the small opening. Then after the engine warms up open the throttle about half-way and pour water into the cup. This will be sucked up into the engine and it has been 45 found in practice that this water will form steam in the cylinders, which loosens and removes every particle of carbon from the engine. If this procedure is repeated once every day for three or four days, while the engine is 50 warm, the engine will be kept clean. The engine should be run fast when the water is poured into the cup for otherwise there is a liability of killing the engine. About one-half gallon of water is used every time. Hot 55 water is a little better than cold water and two heaping tablespoons full of baking soda added to a quart of water will hasten the removal of the carbon.
- 60 What is claimed is:—
- 60 1. An attachment for the purpose set forth comprising an air conducting element in the form of a substantially short tubular member having duplex means intermediate its ends for communication with the vacuum tank and intake manifold of an internal 65
- combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 70
2. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 75
3. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 80
4. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 85
5. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 90
6. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 95
7. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 100
8. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 105
9. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 110
10. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 115
11. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 120
12. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 125
13. An attachment for the purpose set forth comprising an air conducting element in the form of a substantially short tubular member having duplex means intermediate its ends for communication with the vacuum tank and intake manifold of an internal combustion engine, said member further provided with a plurality of angularly disposed tubular extensions adapted to communicate with the atmosphere and each having its free end edge slotted to form a by-pass, the free end edge of each of said extensions constituting a valve seat, a cup shaped valve retainer adjustably mounted on and projecting from the free end of each of said extensions, each of said retainers provided with an opening for establishing communication between an extension and the atmosphere, and a gravity movable globular valve mounted in each retainer and co-acting with a valve seat for controlling the supply of atmospheric air to the intake manifold of the engine during the suction stroke thereof. 130

atmosphere, and a gravity movable globular valve arranged in each of said retainers and engageable against a valve seat on the suction stroke of the engine for controlling the supply of atmospheric air to the intake manifold.

4. An attachment for the purpose set forth comprising an air conducting element in the form of a substantially short tubular member provided with duplex means for communication with the vacuum tank and intake manifold of an internal combustion engine, said member further provided with a plurality of angularly disposed tubular extensions adapted to communicate with the atmosphere and each having its free end provided with diametrically opposed lengthwise extending slots opening at the outer edge of the extension, the free edge of each of said extensions constituting a valve seat and the slots in each extension providing a by-pass for air when a valve is in engagement with its seat, a cup shaped valve retainer adjustably mounted on each of said extensions and having its outer end provided with an opening for establishing communication between the extension and the atmosphere, and a gravity movable globular valve arranged in each of said retainers and engageable against a valve seat on the suction stroke of the engine for controlling the supply of atmospheric air to the intake manifold, the opening in one of said retainers being of greater diameter than the opening in the other of said retainers.

5. An attachment for the purpose set forth comprising an air conducting element having means intermediate its ends for connecting it with the vacuum tank of an internal combustion engine and further for establishing communication between said element and said tank, said element further having means intermediate its ends for establishing communication therebetween and the intake manifold of the engine, said element further including a plurality of angularly disposed tubular extensions adapted to communicate with the atmosphere and with the free end of each of said extensions slotted, the free edge of each of said extensions constituting a valve seat, the said slotted portion of each of said extensions providing a by-pass for air when a valve engages the seat formed by the free edge of the extension, a valve retainer mounted on the free end of each of said extensions and provided with an opening for establishing communication between the extension and the atmosphere, and a gravity movable globular valve arranged in each of the extensions and co-acting with the valve seat for controlling the supply of atmospheric air to the intake manifold on the suction stroke of the engine.

6. An attachment for the purpose set

forth comprising an air conducting element having means intermediate its ends for connecting it with the vacuum tank of an internal combustion engine and further for establishing communication between said element and said tank, said element further having means intermediate its ends for establishing communication therebetween and the intake manifold of the engine, said element further including a plurality of angularly disposed tubular extensions adapted to communicate with the atmosphere and with the free end of each of said extensions slotted, the free edge of each of said extensions constituting a valve seat, the said slotted portion of each of said extensions providing a by-pass for air when a valve engages the seat formed by the free edge of the extension, a valve retainer mounted on the free end of each of said extensions and provided with an opening for establishing communication between the extension and the atmosphere, and a gravity movable globular valve arranged in each of the extensions and co-acting with the valve seat for controlling the supply of atmospheric air to the intake manifold on the suction stroke of the engine, the opening in one of said retainers being of greater diameter than the opening in the other of said retainers.

7. An attachment for the purpose set forth comprising an air conducting element having means intermediate its ends for connecting it with the vacuum tank of an internal combustion engine and further for establishing communication between said element and said tank, said element further having means intermediate its ends for establishing communication therebetween and the intake manifold of the engine, said element further including a plurality of angularly disposed tubular extensions adapted to communicate with the atmosphere and with the free end of each of said extensions slotted, the free edge of each of said extensions constituting a valve seat, the said slotted portion of each of said extensions providing a by-pass for air when a valve engages the seat formed by the free edge of the extension, a valve retainer mounted on the free end of each of said extensions and provided with an opening for establishing communication between the extension and the atmosphere, and a gravity movable globular valve arranged in each of the extensions and co-acting with the valve seat for controlling the supply of atmospheric air to the intake manifold on the suction stroke of the engine, said extensions and retainers provided with means for adjustably positioning the retainers with respect to the extensions.

8. An attachment for the purpose set forth comprising an air conducting element

having means intermediate its ends for connecting it with the vacuum tank of an internal combustion engine and further for establishing communication between said element and said tank, said element further having means intermediate its ends for establishing communication therebetween and the intake manifold of the engine, said element further including a plurality of 10 angularly disposed tubular extensions adapted to communicate with the atmosphere and with the free end of each of said extensions slotted, the free edge of each of said extensions constituting a valve seat, the 15 said slotted portion of each of said extensions providing a by-pass for air when a valve engages the seat formed by the free edge of the extension, a valve retainer mounted on the free end of each of said 20 extensions and provided with an opening for establishing communication between the extension and the atmosphere, and a gravity movable globular valve arranged in each of the extensions and co-acting with the valve 25 seat for controlling the supply of atmospheric air to the intake manifold on the suction stroke of the engine, the opening in one of said retainers being of greater diameter than the opening in the other of 30 said retainers, said extensions and retainers provided with means for adjustably positioning the retainers with respect to the extensions.

9. An attachment for the purpose set forth comprising an air conducting means including a body portion in the form of a substantially short tubular member provided with a pair of outer and an intermediate angularly disposed tubular extension, said 35 intermediate extension providing means for connecting said body portion with the vacuum tank of an internal combustion engine and further for establishing communication between said body portion and said vacuum tank, said tubular member further provided with means disposed at right angles with respect to said intermediate extension for establishing communication 40 between said member and the intake manifold of an internal combustion engine, said outer extensions adapted to communicate with the atmosphere and each having its outer end slotted and further having its outer end constituting a valve seat whereby 45 when the seat is engaged by a valve the slotted portion of the extension will constitute a by-pass for air, a cup shaped valve retainer mounted on the outer end of each of said outer extensions and provided at its 50 outer end with an opening for establishing communication between the outer extension and the atmosphere, and a gravity movable globular valve arranged in each of said 55 retainers and engageable against a valve seat for controlling the supply of atmospheric 60

air to the intake manifold on the suction stroke of the engine.

10. An attachment for the purpose set forth comprising an air conducting means including a body portion in the form of a substantially short tubular member provided with a pair of outer and an intermediate angularly disposed tubular extension, said intermediate extension providing means for connecting said body portion with the vacuum tank of an internal combustion engine and further for establishing communication between said body portion and said vacuum tank, said tubular member further provided with means disposed at right angles with respect to said intermediate extension for establishing communication between said member and the intake manifold of an internal combustion engine, said outer extensions adapted to communicate with the atmosphere and each having its outer end slotted and further having its outer end constituting a valve seat whereby 70 when the seat is engaged by a valve the slotted portion of the extension will constitute a by-pass for air, a cup shaped valve retainer mounted on the outer end of each of said outer extensions and provided at its outer end with an opening for establishing communication between the outer extension and the atmosphere, and a gravity movable globular valve arranged in each of said retainers and engageable against a valve seat for controlling the supply of atmospheric air to the intake manifold on the suction stroke of the engine, the opening in one of said retainers being of greater diameter than the opening in the other of 75 said retainers. 80

11. An attachment for the purpose set forth comprising an air conducting means including a body portion in the form of a substantially short tubular member provided with a pair of outer and an intermediate angularly disposed tubular extension, said intermediate extension providing means for connecting said body portion with the vacuum tank of an internal combustion engine and further for establishing communication between said body portion and said vacuum tank, said tubular member further provided with means disposed at right angles with respect to said intermediate extension for establishing communication between said member and the intake manifold of an internal combustion engine, said outer extensions adapted to communicate with the atmosphere and each having its outer end slotted and further having its outer end constituting a valve seat whereby 85 when the seat is engaged by a valve the slotted portion of the extension will constitute a by-pass for air, a cup shaped valve retainer mounted on the outer end of each of said outer extensions and provided at its outer end with an opening for establishing communication between the outer extension and the atmosphere, and a gravity movable globular valve arranged in each of said retainers and engageable against a valve seat for controlling the supply of atmospheric air to the intake manifold on the suction stroke of the engine, the opening in one of said retainers being of greater diameter than the opening in the other of 90 said retainers. 95

12. An attachment for the purpose set forth comprising an air conducting means including a body portion in the form of a substantially short tubular member provided with a pair of outer and an intermediate angularly disposed tubular extension, said intermediate extension providing means for connecting said body portion with the vacuum tank of an internal combustion engine and further for establishing communication between said body portion and said vacuum tank, said tubular member further provided with means disposed at right angles with respect to said intermediate extension for establishing communication between said member and the intake manifold of an internal combustion engine, said outer extensions adapted to communicate with the atmosphere and each having its outer end slotted and further having its outer end constituting a valve seat whereby 100 when the seat is engaged by a valve the slotted portion of the extension will constitute a by-pass for air, a cup shaped valve retainer mounted on the outer end of each of said outer extensions and provided at its outer end with an opening for establishing communication between the outer extension and the atmosphere, and a gravity movable globular valve arranged in each of said retainers and engageable against a valve seat for controlling the supply of atmospheric air to the intake manifold on the suction stroke of the engine, the opening in one of said retainers being of greater diameter than the opening in the other of 105 said retainers. 110

13. An attachment for the purpose set forth comprising an air conducting means including a body portion in the form of a substantially short tubular member provided with a pair of outer and an intermediate angularly disposed tubular extension, said intermediate extension providing means for connecting said body portion with the vacuum tank of an internal combustion engine and further for establishing communication between said body portion and said vacuum tank, said tubular member further provided with means disposed at right angles with respect to said intermediate extension for establishing communication between said member and the intake manifold of an internal combustion engine, said outer extensions adapted to communicate with the atmosphere and each having its outer end slotted and further having its outer end constituting a valve seat whereby 115 when the seat is engaged by a valve the slotted portion of the extension will constitute a by-pass for air, a cup shaped valve retainer mounted on the outer end of each of said outer extensions and provided at its outer end with an opening for establishing communication between the outer extension and the atmosphere, and a gravity movable globular valve arranged in each of said retainers and engageable against a valve seat for controlling the supply of atmospheric air to the intake manifold on the suction stroke of the engine, the opening in one of said retainers being of greater diameter than the opening in the other of 120 said retainers. 125

14. An attachment for the purpose set forth comprising an air conducting means including a body portion in the form of a substantially short tubular member provided with a pair of outer and an intermediate angularly disposed tubular extension, said intermediate extension providing means for connecting said body portion with the vacuum tank of an internal combustion engine and further for establishing communication between said body portion and said vacuum tank, said tubular member further provided with means disposed at right angles with respect to said intermediate extension for establishing communication between said member and the intake manifold of an internal combustion engine, said outer extensions adapted to communicate with the atmosphere and each having its outer end slotted and further having its outer end constituting a valve seat whereby 130 when the seat is engaged by a valve the slotted portion of the extension will constitute a by-pass for air, a cup shaped valve retainer mounted on the outer end of each of said outer extensions and provided at its outer end with an opening for establishing communication be-

between the outer extensions and the atmosphere, and a gravity movable globular valve arranged in each of said retainers and engageable against a valve seat for controlling the supply of atmospheric air to the intake manifold on the suction stroke of the engine, said retainers and outer extensions provided with means to provide for the adjusting of the retainers with respect to said outer extensions.

12. An attachment for the purpose set forth comprising an air conducting means including a body portion in the form of a substantially short tubular member provided with a pair of outer and an intermediate angularly disposed tubular extension, said intermediate extension providing means for connecting said body portion with the vacuum tank of an internal combustion engine and further for establishing communication between said body portion and said vacuum tank, said tubular member further provided with means disposed at right angles with respect to said intermediate extension for establishing communication between said member and the intake manifold of an

internal combustion engine, said outer extensions adapted to communicate with the atmosphere and each having its outer end slotted and further having its outer end constituting a valve seat whereby when the seat is engaged by a valve the slotted portion of the extension will constitute a by-pass for air, a cup shaped valve retainer mounted on the outer end of each of said outer extensions and provided at its outer end with an opening for establishing communication between the outer extension and the atmosphere, and a gravity movable globular valve arranged in each of said retainers and engageable against a valve seat for controlling the supply of atmospheric air to the intake manifold on the suction stroke of the engine, the opening in one of said retainers being of greater diameter than the opening in the other of said retainers, said retainers and outer extensions provided with means to provide for the adjusting of the retainers with respect to said outer extensions.

In testimony whereof, I affix my signature hereto.

LEO G. STRANSKY.
